COMBINED TABLE AND BENCHES

William C. Demmien, Williamsport, Pa.

Application September 18, 1943, Serial No. 503,007

4 Claims. (Cl. 155—124)

This invention relates to improvements in combined tables and benches or the like and the primary object of the invention is to provide a sturdy combination of this type in which the space beneath the table will not be obstructed, that is, will allow ample leg room.

Another object is to supply combination furniture of this character which may be shipped in knock-down condition and set up by unskilled labor.

A further object is to furnish a combined table and benches of pleasing appearance and having sufficient strength to withstand heavy weights or rough use, such as may be encountered outdoors.

A still further object is to produce a simple and inexpensive combination of this type and yet one which will be exceedingly useful for the purposes for which it is designed.

With the foregoing objects outlined and with other objects in view which will appear as the description proceeds, the invention consists in the novel features hereinafter described in detail, illustrated in the accompanying drawings and more particularly pointed out in the appended claims.

Referring to the drawings:

Fig. 1 is a top plan view of one example of my combined table and benches.

Fig. 2 is a side elevation of the same.

Fig. 3 is a top plan view of a modification.

Fig. 4 is a side elevation of the structure shown in Fig. 3.

Fig. 5 is a top plan view of another modification.

Fig. 6 is a side elevation of the same.

In the embodiment of the invention illustrated in Figs. 1 and 2, 6 designates end legs of benches 7 of arc shape. Four of these benches are arranged as shown in Fig. 1 to form substantially a circle with the ends of the benches spaced apart as indicated at 8 to allow for entrance and departure. To facilitate assembling or dismantling, the top of each bench is connected to its legs by any suitable means such as screws 9.

A vertically disposed beam 10 extends diametrically across the circle formed by the benches and is supported at the medial portions of a pair of oppositely disposed benches and has its end portions secured to the seat portions thereof by bolts 11 or the like. Another beam 12 formed by two girders 13 is arranged at right angles to the beam 10 and is firmly secured to the latter and to the medial portion of the seats of the

other pair of benches by any suitable means, indicated at 14. The lower edge of each beam rises from its end portions towards its medial portion for leg room purposes.

5 A preferably circular table top 15 is mounted horizontally on the beams and each of the latter extends diametrically across the bottom surface or the top so that persons occupying the benches may readily use the table top. The top may be secured to the beam by any suitable means. For example, the top may be provided on its underside with a spaced cleats 15a secured thereto by screws 15b or the like and they may straddle the beam and be connected to the latter by bolts 15c. The cleats may be reinforced by triangular pieces 15d secured in place by any preferred means.

It will be understood from the foregoing that all of the parts are rigidly secured together 20 preferably by means permitting detachment of one part from another so that the structure may be shipped in knock-down condition and then set up by unskilled labor.

Instead of adopting the circular scheme indicated in Figs. 1 and 2, I may follow the square form illustrated in Figs. 3 and 4. In this embodiment, each bench 17 instead of being of arc shape will be straight and the benches at opposite sides of the table will be arranged parallel to one 30 another to accord with the parallel side edges of the rectangular table top 18. Of course, the beams in this form may be the same as those in Figs. 1 and 2.

In the modification illustrated in Figs. 5 and 6, 35 only a single pair of benches 19 are employed in connection with a rectangular table top 20. They are arranged at opposite sides of such table and support a single beam 21 which has its ends resting on and secured to the benches. The beam supports the table top and the latter has portions arranged symmetrically at opposite sides of the beam. In this form of the invention, as well as in the other forms, if desired, a single table leg 22 may be arranged directly beneath 40 the central portion of the table top and terminates at the same level as the lower ends of the bench legs 23. The table leg is preferably bifurcated at its upper portion so as to receive the beam, and braces 24 are arranged at right angles to the beam and each has its ends connected respectively, by any suitable means, to the table leg and to the table top, so that they, 45 in effect, form a second beam.

In any form of the invention, the benches may 50 be provided with backs as indicated at 25 and it

will be manifest that the benches, beams, legs and table tops may be made of various shapes.

From the foregoing it is believed that the construction and advantages of my combined furniture may be readily understood and it will be apparent that changes may be made in the details disclosed without departing from the spirit of the invention as expressed in the claims.

What I claim and desire to secure by Letters Patent is:

1. Combination furniture comprising a table top having spaced parallel cleats rigidly secured to the bottom thereof and arranged at opposite sides of the middle of the top, a beam structure supporting the top and consisting of a pair of beams arranged at right angles to one another, each beam extending across the top from one side thereof to an opposite side thereof and having end portions projecting in opposite directions from the top, the table top and cleats forming a saddle straddling one of said beams, means rigidly and detachably securing said cleats to the last-mentioned beam, and pairs of confronting benches having seat portions positioned at a lower elevation than said top and rigidly supporting said beams, the lower edge of each beam rising from its end portions towards its medial portion to provide leg room beneath the table top.

2. Combination furniture comprising a table top having spaced parallel cleats rigidly secured to the bottom thereof and arranged at opposite sides of the middle of the top, a beam structure supporting the top and consisting of a pair of beams arranged at right angles to one another, each beam extending across the top from one side thereof to an opposite side thereof and having end portions projecting in opposite directions from the top, the table top and cleats forming a saddle straddling one of said beams, means rigidly and detachably securing said cleats to the last-mentioned beam, and pairs of confronting benches having seat portions positioned at a lower elevation than said top and rigidly supporting said beams, the lower edge of each beam having an arc-shaped portion between

the benches which support the beam to provide leg room beneath the table top.

3. Combination furniture comprising a table top having spaced parallel cleats rigidly secured to the bottom thereof and arranged at opposite sides of the middle of the top, a beam structure supporting the top and consisting of a pair of beams arranged at right angles to one another, each beam extending across the top from one side thereof to an opposite side thereof and having end portions projecting in opposite directions from the top, the table top and cleats forming a saddle straddling one of said beams, means rigidly and detachably securing said cleats to the last-mentioned beam, pairs of confronting benches having seat portions positioned at a lower elevation than said top and rigidly supporting said beams, the lower edge of each beam rising from its end portions towards its medial portion to provide leg room beneath the table top, and means detachably securing the ends of the beams to the benches.

4. Combination furniture comprising a substantially circular table top having spaced parallel cleats rigidly secured to the bottom thereof and arranged at opposite sides of the middle of the top, a beam structure supporting said top and consisting of a pair of beams arranged at right angles to one another, each beam extending diametrically across the top from one side thereof to an opposite side thereof and having end portions projecting in opposite directions from the top, the table top and cleats forming a saddle straddling one of said beams, means rigidly and detachably securing said cleats to the last-mentioned beam, and pairs of confronting arc-shaped benches having seat portions positioned at a lower elevation than said top and rigidly supporting said beams, the ends of the benches being spaced from one another to facilitate occupation of the benches, the lower edge of each beam rising from its end portions towards its medial portion to provide leg room beneath the table top.
